UNITED STATES PATENT OFFICE.

TIBURCE CATALA, OF ENGLEWOOD CLIFFS, NEW JERSEY.

JEWELRY CASE.

Application filed March 6, 1926. Serial No. 92,906.

This invention relates to a jewelry case.

An object of this invention is to provide a jewelry case so constructed that when the cover is opened to display the jewelry there within, the article of jewelry will be moved to an inclined position for the better display thereof, whereas when the cover is down the article will lie flat within the box or casing.

10 A further object is the provision of a means to achieve the above operation with a minimum number of parts so constructed and arranged that the cost of the casing is very negligibly increased, if any.

15 The invention is illustrated in the drawings, of which—

Figure 1 is a perspective view of the casing;

20 Figure 2 is a section taken on the line 2—2 of Figure 1, showing the casing in open position;

Figure 3 is a similar section showing the case in closed position.

The form of the invention shown in the drawings is a preferred form, although it is understood that modification in the construction and arrangement of the parts and in the character of the materials used may be adopted without departing from the spirit of the invention as set forth in the appended claims.

In its general aspect the invention comprises a case having a body portion and a hinged cover. To the cover is connected a false bottom which normally lies flat within the body portion, but which when the cover is opened is moved to an inclined position so that the jewelry supporting pad which lies over the false bottom will be moved to an inclined position when the cover is opened, thus displaying the jewelry more effectively than if the pad were lying flat.

In the preferred form of the invention I show a casing having a body portion 10 and a hinged cover 11, within which is to be disposed a jewelry supporting pad 12 of any suitable type. Within the bottom of the casing is disposed a false bottom plate 13, which is constructed and adapted to fold along the lines indicated by the numerals 14, 15 and 16. The edge 16 of the false

bottom is connected to a rigid plate 17 projecting from one edge of the cover.

The other edge 18 of the false bottom plate is adapted to lie within a channel or grooved portion formed by bending over as at 19 the edge of a lining 20. When the cover is down as shown in Figure 3, the false bottom plate lies flat on the bottom lining 20 of the body portion of the casing and the pad is disposed flat beneath the cover. However, when the cover is moved to its open position as shown in Figure 2, the stiff portion 17 projecting from the cover will pull on the false bottom plate and move it to the inclined position shown in Figure 2, when the front edge of the false bottom still retained in the groove, so as to hold it down on the bottom. The pad 12 will therefore be held in the inclined position, when the jewelry thereon will be better displayed.

What I claim is:

1. A jewelry casing which comprises a body portion, a cover hinged thereto, a stiff plate projecting from the cover, a lining in the body portion having one edge bent over to form a groove, a false bottom plate foldable along certain predetermined lines having one edge lying within said groove and the other edge connected to the plate projecting from the cover, an article supporting pad normally disposed on the false bottom plate, the false bottom plate adapted to be moved to an inclined position when the cover is open to support the article supporting pad in an inclined relationship with respect to said body portion.

2. A case comprising a body in the form of a receptacle, a cover hingedly connected with the body, a foldable false bottom connected with the cover, the false bottom normally adapted to lie flat within the body, and means slidably retaining a portion of the false bottom, so that in the movement of the cover to an opened position, the false bottom will be moved to an inclined position.

3. A case comprising a body in the form of a receptacle, a cover hingedly connected with the body, a foldable false bottom connected with the cover, the false bottom nor-

mally adapted to lie flat within the body, of the false bottom, to an inclined position means slidably retaining a portion of the when the cover is in its opened position, and false bottom, so that in the movement of to a position in which it lies on the false 10 cover to an opened position, the false bottom when the cover is in its closed will be moved to an inclined position, and an article supporting pad within the body movable in response to the movement

TIBURCE CATALA.
